UNITED STATES PATENT OFFICE.

CHARLES S. BIRD, OF WALPOLE, MASSACHUSETTS.

APPARATUS FOR THE MANUFACTURE OF ROOFING FABRICS.

SPECIFICATION forming part of Letters Patent No. 690,349, dated December 31, 1901.

Application filed October 25, 1901. Serial No. 80,025. (No model.)

To all whom it may concern:

Be it known that I, CHARLES S. BIRD, of Walpole, Norfolk County, Massachusetts, have invented a new and useful Improvement in Apparatus for the Manufacture of Roofing Fabrics, of which the following is a specification.

My invention has to do with that portion of an apparatus for the manufacture of roofing fabrics in and by which the fabric web is saturated with the waterproofing material. It will first be described in connection with the drawing accompanying and forming part of this specification and will then be more particularly pointed out in the claims.

15 The drawing represents in side elevation, partly in section, so much of an apparatus embodying my invention as needed for the purpose of explaining the invention.

1 is the roll of dry paper or other fabric to be saturated with the waterproofing material.

2 is the saturation-pan containing the hot asphaltum liquor or other material with which the web of paper is to be saturated.

3 is a heating-drum mounted to revolve in suitable bearings. It is preferably steam-heated, for which purpose it is made hollow and steam-tight, the steam from any suitable source being admitted into the interior of the drum through one of the journals of the drum

30 by means of connections and fittings well known to the skilled artisan. The degree of heat may vary; but I usually carry in the drum a steam-pressure of from twenty to fifty pounds, which imparts to the comparatively

35 thin metallic walls of the drum a very high heat. The drum, which is arranged over the saturation-pan, is of considerable diameter—say four feet or more—so that the paper web may have prolonged contact with it.

40 4 5 are guide-rollers in the saturation-pan, located below the heating-drum 3. The paper to be saturated passes from the roll 1 down under the first guide-roller 4, thence up and over the heating-drum, thence down again

45 into the saturation-pan under the second guide-roller 5, and thence from the saturation-pan. The paper, it will be noted, has an extended and prolonged contact with the highly-heated periphery of the drum.

50 6 represents pressure-rollers mounted in a suitable stand. They are hollow and steam-heated. The web of paper as it emerges from

the saturation-pan is led to and passes between these rollers, after which it goes to the other portions of the apparatus, in which it is 55 further treated and finished. These portions of the apparatus, however, are omitted from the drawing, inasmuch as they form no part of my present invention.

The saturation-pan is kept suitably supplied with hot asphaltum or other waterproofing liquor, the heat of which may be maintained in any of the ways usually employed in apparatus of this general kind. The paper drawn from the roll 1 passes down 65 into the hot liquor in the saturation-pan and under the first guide-roller 4 therein and thence up and over the heater 3. In its passage through the bath it is thickly covered on both sides with the hot waterproofing liquor, 70 which has also partly penetrated the paper, and in this condition it reaches the heater-drum 3. During its prolonged contact with said drum, up and over and around which it passes, as indicated in the drawing, the great 75 heat of the drum forces the waterproofing material into and causes it to thoroughly permeate the paper. The paper thence passes down under the second guide-roller 5 and into the bath again, so that any unfilled pores may 80 receive the waterproofing material, and it thence passes to the steam-heated pressure-rollers 6, which serve to remove the surplus waterproofing material and to dry the surface of the paper.

85 What is new in the described apparatus over and above what has before been employed is the heating-drum 3. By its use I am enabled with but one passage of the paper through the saturation-tank to thoroughly 90 and effectively saturate the thickest web that is ordinarily used for roofing purposes. Heretofore this has not been practicable.

So far as I am aware thick roofing paper has heretofore been produced in one of two 95 ways—either by running thin webs of paper singly through the saturation-pan once and then afterward putting together two, three, or more plies of such treated paper and uniting them by means of interposed adhesive 100 material in a web of the desired thickness, or by making the web or paper of the desired thickness in the first instance and then passing this thick web back and forth many times

in the saturation-pan, running the web for this purpose over and around a series of guide-rollers at the ends of the pan, so that it shall lie therein in the shape of a series of super-
5 posed folds or layers, so as to insure the ex-
posure of the paper to the action of the bath
for a sufficient period to effect saturation, after
which it is conducted to and passed between
10 steam-heated pressure-rollers similar to roll-
ers 6. Not only is this a complicated and
troublesome operation, but by running the
paper this long distance through the hot liq-
uor there is great danger of breaks and dam-
aged material, because the paper when thus
15 wet is liable to tear, particularly when subject-
ed to the very considerable strain which comes
upon it by reason of the tortuous path in
which it is carried back and forth in the bath
around the guide-rollers. The steam-heated
20 pressure-rollers through which it has been
customary heretofore to conduct the thus-
treated web after the latter has left the sat-
uration-pan are not effective to drive the
liquor into the paper, because they are small
25 and the paper has only brief contact with
them, while they must also be very heavy and
made with thick walls, which renders it diffi-
cult to heat them properly. All of these dis-
advantages are obviated by my invention,
30 which enables me by passing the paper for a
brief period and for a short distance only
through the bath to thoroughly saturate the
thickest paper web which is usually employed
for roofing purposes, and, in fact, I am thus
35 enabled to get more of the waterproofing ma-
terial into the thick web than is practicable
in any other apparatus of which I have knowl-
edge, the waterproofing material driven into
the paper equaling the latter in weight.
40 The movement of the paper through the ap-
paratus is accomplished mainly by the pres-
sure-rollers 6, which are power-driven for this
purpose. Similarly the drum 3 is power-
driven and should be so geared as to revolve
45 at the same surface speed as the pressure-
rollers.

It is not indispensable that the paper should
pass down a second time into the waterproof-
ing-bath, and after passing the paper down
under the guide-roller 4 and thence up over 50
the heating-drum it could without departure
from my invention be led directly to the pres-
sure-rollers 6; but I prefer to immerse the
paper a second time in the bath for reasons
hereinbefore stated. 55

I may mention also as one of the advantages
of my invention that by the use of a heating-
drum in the manner hereinbefore described
I am enabled to successfully treat cheaper
kinds of paper, felt, &c., which heretofore it 60
has not been practicable to effectively satu-
rate.

What I claim herein as new and of my own
invention is—

1. In apparatus for the manufacture of roof- 65
ing fabric, the combination with the satura-
tion-pan containing the waterproofing liquor,
and the pressure-rollers for removing the sur-
plus liquor from the web, of a heating-drum
over, around and in contact with which the 70
fabric web is conducted after it has been im-
mersed in the waterproofing liquor and before
it reaches the pressure-rollers, substantially
as and for the purposes hereinbefore set forth.

2. In apparatus for the manufacture of roof- 75
ing fabric, the combination with the satura-
tion-pan containing the waterproofing liquor,
and the pressure-rollers for removing the sur-
plus liquor from the web, of a heating-drum,
and guides whereby the fabric web is con- 80
ducted first into the waterproofing - bath,
thence out therefrom and over and around
the heating-drum, thence down again into the
waterproofing-bath, and thence out therefrom
to the pressure-rollers substantially as and 85
for the purposes hereinbefore set forth.

In testimony whereof I have hereunto set
my hand this 19th day of October, 1901.

CHARLES S. BIRD.
